UNITED STATES PATENT OFFICE.

WALTER W. EASTMAN, OF HILL, NEW HAMPSHIRE, ASSIGNOR TO FRANK R. WOODWARD, OF HILL, NEW HAMPSHIRE.

LANTERN ATTACHMENT.

1,081,028.

Specification of Letters Patent.

Patented Dec. 9, 1913.

Application filed January 28, 1913. Serial No. 744,659.

To all whom it may concern:

Be it known that I, WALTER W. EASTMAN, a citizen of the United States of America, residing at Hill, in the county of Merrimack, 5 and State of New Hampshire, have invented certain new and useful Improvements in Lantern Attachments, of which the following is a specification.

This invention relates to certain new and 10 useful improvements in lantern attachments and more particularly to a signal attachment therefor; the object being to provide an attachment which is so constructed that the same will adjust itself to any sized lantern, thereby enabling the attachment to be 15 used in connection with various styles of lanterns.

A further object of the invention is to provide an attachment which comprises a 20 plate carrying a colored glass or bull's-eye, having attaching members pivotally carried thereby for securing the same, in position upon the tubes of the lantern frame in order to provide a signal lantern which is especially adapted to be used on a vehicle for the 25 side or rear lamp.

Another object of the invention is to provide a device which is exceedingly simple and cheap in construction and one in which 30 the attaching members can be folded so as to lie flat, thereby enabling the attachment to be folded into compact form for shipping or transportation purposes.

I am aware that I am not the first to provide 35 a signal attachment for a lantern having means for securing the same to the frame of the lantern; but in devices of this character previously constructed, the device was not provided with grasping or attaching members which would expand or contract to fit any sized lantern, nor were means provided for allowing said members to be folded for shipping purposes.

Other and further objects and advantages 40 of the invention will be hereinafter set forth and the novel features thereof defined by the appended claims.

In the drawings—Figure 1, is a perspective view of a lantern showing the application 45 of my improved attachment thereto and Fig. 2, is a perspective view of the attachment detached.

Like numerals of reference refer to like 50 parts in the several figures of the drawings. 55 In the drawings 1 indicates a sheet metal

plate formed of any suitable metal having a central opening 2 over which is arranged a colored glass 3 which is secured in position by bending the upper and lower edges of the plate back upon itself, as clearly 60 shown at 4 and 5; the central portion being slightly offset as shown at 6 forming a central pocket to receive the ends of the plate 3 so as to prevent longitudinal movement of the plate after being placed in position. 65 The side edges of the plate are bent back upon itself as shown at 7 to form a finished edge. The bent back portion 4 of the plate 1 forms an eye in which the connecting bar of a substantially U-shaped spring frame 8 is 70 pivotally mounted; said frame being provided with coil portions 9 in order to allow the free ends to expand to accommodate different sized lanterns and the free ends of said frame are provided with substantially 75 semi-circular portions 10 which are adapted to embrace the vertical tubes of the lantern frame, as clearly shown in Fig. 1.

It will be seen that by mounting the wire frame within the eye of the plate in this 80 manner, it can be folded flat upon the plate when not in use. The bent back portion 5 at the lower edge of the plate forms an eye in which the connecting member of the substantially U-shaped frame 11 is pivotally 85 mounted; said frame being provided with coil portions 12 and the free ends thereof are provided with substantially U-shaped portions 13 slightly twisted as shown, to embrace the tubes of the lantern frame at 90 the junction of the vertical and horizontal tubes thereof and when inserted in position thereon, they are subjected to a twist in order to exert torsional stress so as to hold the plate in position, as shown in Fig. 1. 95 thereby preventing the same from moving in any way. It will be seen by this construction, that by changing the angles of the frames 8 and 11, the plate can be held at the desired distance from the globe of the lantern as by spreading the free ends of the frames, the plate will be drawn toward the globe or by moving the same together, or into parallelism and the plate will be forced away from the globe and this enables 100 frames formed of fixed sizes to be applied to any sized lantern.

The coil portions 9 and 10 of the frames 8 and 11 prevent longitudinal movement of the connecting bars of the frame within the 110

eyes and also exert a spring pressure whereby substantially spring frames are formed for gripping the frame of the lantern in order to hold the signal plate in the desired position.

- 5 From the foregoing description, it will be seen that I have provided a signal attachment for a lantern with a pair of pivotally mounted spring frames having gripping portions at the free ends thereof capable of gripping the frame of a lantern in such a manner as to hold the signal plate firmly in position thereon without any danger of the plate being accidentally detached by the jolting of the vehicle to which it is attached, and this attachment is especially adapted to be used in connection with a lantern holder as disclosed in my Patent #1,042,898, granted to me October 29, 1912.
- 10 20 By constructing an attachment as hereinbefore set forth, the same can be attached to a lantern carried by various forms of holders without interfering with the support in any way.
- 15 25 I claim:
1. A signal attachment for lanterns comprising a plate having an opening, a pocket formed on said plate to each side of said opening, a signal glass arranged over said opening in said pockets, and a pair of spring frames pivotally mounted upon said plate, said frames being provided with gripping portions at their free ends for engaging the frame of a lantern.
  2. An attachment for lanterns comprising a plate having an opening, a glass arranged over said opening, the upper and lower edges of said plate being bent back upon the glass, said bent-back portions forming horizontal eyes, and spring frames mounted in said eyes having gripping por-

tions at their free ends for engaging the frame of a lantern.

3. A lantern attachment comprising a signal plate having its upper and lower edges bent back to form eyes, said bent-back portions being offset to form pockets, said plate having an opening formed therein between said pockets, a glass arranged in said pockets, substantially U-shaped spring frames pivotally mounted in said eyes, the free ends of said frame being provided with gripping portions for engaging the frame of a lantern.

4. A lantern attachment comprising a signal plate, frames pivotally carried by said plate, the free ends of one of said frames being provided with semi-circular portions for engaging the vertical tubes of a lantern frame, the free ends of the other frame being provided with substantially U-shaped portions arranged at an angle to the semi-circular shaped portions, and subjected to a torsional stress when placed in position upon a lantern frame.

5. A lantern attachment comprising a plate having its edges turned back upon itself and provided with a central opening, a signal glass arranged over said opening and secured in position thereon by two of the bent-back edges thereof, wire frames arranged under the bent-back portions of said plate, having coil portions and provided at their free ends with gripping portions for engaging the frame of a lantern.

In testimony whereof I affix my signature in presence of two witnesses.

WALTER W. EASTMAN.
